MACHINE FOR RAMMING THE BALLAST OF RAILWAY LINES

Paul Allemann, Renens, Switzerland, assignor to Matériel Industriel S.A., Lausanne, and Constructions Mécaniques S.A. Renens, Renens, Switzerland

Filed Jan. 22, 1958, Ser. No. 710,465

Claims priority, application Switzerland Feb. 4, 1957

1 Claim. (Cl. 104—12)

It is known that the ramming machines for railway lines very often comprise removable tools which can be mounted on a certain number of vibrating tool-carriers, having the shape of arms, which are arranged in pairs opposite to one another on either side of the sleeper which is to be rammed and which are generally arranged on one or more supporting members, called mobile frames because they can be displaced in relation to the fixed frame of the vehicle in order that the tools may be sunk into the ballast. It is known that the ramming action, facilitated by the vibration of the tools, is obtained in particular by successively moving the tool spades towards one another and away from one another which assembles and packs the stones of the ballast to a compact mass, called a mould, under each sleeper in the neighborhood of each of the rows of rails.

In the rammers which are called hydraulic or pneumatic, these motions, respectively called closing and opening motions, of the tool-carriers are controlled by a fluid acting by its pressure in variable volume chambers.

In the hydraulic or pneumatic rammers known as vibrating frame rammers, the two arms of each pair are articulated on an auxiliary supporting member which is made to vibrate by means of a generator of vibrations of any type and is then secured to the mobile frame proper, i.e., to the frame which is adjustable in height as we have seen above, preferably by means of damping members in order to reduce the vibrating masses to a minimum, which offers all the evident advantages of such an arrangement.

Actually there is in this type of machine no known satisfactory system enabling symmetrical closing motions, i.e., a conjugated closing motion to be imparted to the two tool-carrying arms, because those based on the interdependence of the hydraulic control itself lead to designs which are too complicated, delicate and costly for practical requirements, and those making use of a mechanical interdependence of the two arms, which employ a system of elbowed tool-carrying arms connected by a multiplicity of rods, i.e., comprising several rigid elements articulated in series so as to form a kinematic chain, which require, in addition, a device to guide at least one intermediate articulation in relation to the vibrating frame, are badly adapted for the purpose owing to the elasticity of the mechanism and to the backlash which inevitably occurs in the articulations, thus causing sensible losses in the vibration of the tool-carriers in addition to the other aforementioned disadvantages.

The present invention aims at remedying these defects of the hydraulic and pneumatic rammers, and in particular of those with a vibrating frame. Its object is a machine for ramming the ballast of railway lines, of the type comprising means controlled by a fluid under pressure for producing the motions towards one another and away from one another of at least one pair of ramming tools, characterized in that at least one member ensuring the mechanical interdependence is provided to connect the two tool-carrying arms of a same pair of tools, in order to ensure a conjugated motion of these tools, this member,

2

which can be made in several parts being articulated solely to these tool-carrying arms.

The single figure of the accompanying drawing illustrates, schematically and by way of an example, an embodiment of the machine according to the invention.

5 In 1 may be seen two tool-carriers in the shape of rectilinear arms respectively articulated in 2 and 3 to the rod 7 of a piston and to a cylinder 8 in which this piston slides. In 4 may be seen the tools (spades) secured to the lower extremities of the arms 1. In 5 can be seen a sleeper under which the ballast (which has not been shown) has to be rammed by the tools 4. The ducts 11 serve to supply the fluid and evacuate it from one side and the other of the piston in the cylinder 8.

15 The arms 1 are articulated in the middle, in 6, to a body 12 called the vibrating frame and which is represented by a plate in the shape of a U placed upside down.

This vibrating frame is secured by means of damping components 13, on a frame which has not been shown and 20 which is mobile vertically in order to ensure the sinking motion of the tools 4 into the ballast, the extraction of these tools from the ballast and to allow them to be lifted above the sleeper 5, in order that the machine and with it the tools 4 may be moved over to the next sleeper.

25 A vibrator, constituted in the embodiment shown by an electric motor 10 driving an eccentric 9, is secured to the frame 12 and consequently imparts to the latter a vibrating motion which it transmits to the arms 1 and consequently to the tools 4. This vibrator could be of 30 a type different from that comprising an unbalance and an electric motor.

The arms 1 are connected to one another so as to be mechanically interdependent by a member, constituted in this embodiment by a rod 14, articulated to points 15,

35 respectively 16 of the arms 1, preferably situated at equal distances from the articulations 6, but the one above and the other below the respective articulation. It is easy to understand that thus, when the fluid under pressure is introduced into the part of the cylinder 8 which 40 is situated to the right of the piston 7, the tools 4 are not only compelled to move towards one another, but that in addition, the motion of these tools can, according to the proportions chosen for the different parts, be practically symmetrical within the extent of the working movement. An abnormal swinging motion of the tool-carriers under the influence of the weights concerned and 45 above all under the action of the unequal resistances encountered by the two tools 4 in the ballast, is thus avoided.

This advantage of having a conjugated practically symmetrical motion of the tools is of importance for the 50 quality of the ramming action. Up to the present, in the hydraulic or pneumatic rammers which were principally designed so as to limit the ramming pressure, this symmetrical motion was not ensured, as has been mentioned 55 above.

In a variant, the interconnecting rod can be provided at 14a, i.e., symmetrically with respect to the rod 14, as shown by the dot and dash lines.

60 In another variant, the axis of the piston 7 and cylinder 8 controlling the opening and closing motion of the tools could be arranged obliquely, for instance in order to allow the articulations 3 and 6 of the right-hand arm 1 to be replaced by a common articulation. This construction 65 would allow the articulations 6 of the left-hand arm and 16 to be arranged at the same height above the ballast. The shape of the vibrating frame 12 would in that case have to be modified in consequence, the right-hand point 6 (coinciding with 3) would be placed higher than 70 the left-hand point 6 and that part of the right-hand arm 1 situated above the articulation 6 would be suppressed.

It will be remarked that owing to the fact that the tools

all vibrate under the control of the frame, they vibrate synchronously and in phase. The rear face of a tool 4 thus periodically receives from the ballast a thrust which tends to close the tool-carriers and counteracts the effect of the ballast compressed by the opposite tool, whence 5 the possibility of using an elastic fluid (gas).

The vibrating frame 12 could obviously be made to carry more than one pair of tool-carrying arms.

The invention is not limited to the case of a vibrating tool-carrying frame. The vibration of the tools could 10 also be controlled individually for each tool.

What I claim is:

Ramming apparatus comprising opposed ramming tools, tool carriers supporting said ramming tools, a supporting frame, each of said tool carriers being pivoted on 15 said frame, piston and cylinder means coupled to said tool carriers on the same side of the connection between the tool carrier and the frame and responsive to a pressure medium for oscillating said tools toward and away from each other, and a connecting rod connected solely 20 between said tool carriers, said rod being connected to

one carrier above the connection of the latter to said frame and to the other carrier below the connection of the latter to said frame and being spaced the same distance from the pivot connection point between the tool carrier and the frame, said rod insuring a correlated movement of said carriers.
